UNITED STATES PATENT OFFICE.

LEWIS W. CHRISTOPHEL, OF UNIVERSITY CITY, MISSOURI.

HINGE.

1,132,560.

Specification of Letters Patent. Patented Mar. 23, 1915.

Application filed July 27, 1914. Serial No. 853,265.

To all whom it may concern:

Be it known that I, LEWIS W. CHRISTOPHEL, a citizen of the United States, residing at University City, St. Louis county, 5 Missouri, have invented a new and useful Hinge, of which the following is a specification.

This invention relates to hinges and consists of the novel construction, combination 10 and arrangement of parts possessing the novel qualities and serving the useful functions hereinafter fully described.

An object of the invention is to provide an improved hinge in which portions of the 15 leaves are retained at a distance from the surfaces to which the hinge is secured, in combination with means for rigidly and securely supporting the raised portions of the hinge to prevent compression thereof, and 20 means for distributing the stresses properly upon the screws or other elements by which the hinge is secured in place.

Another object is to provide a hinge of the type mentioned in which the outer surfaces 25 of both leaves of the hinge are in the same plane, and in which one of the leaves is secured to a surface which is beyond or inwardly from the surface to which the other leaf of the hinge is attached, in combination with devices for supporting the 30 last named leaf to prevent compression of the outer or raised portion thereof, and elements for receiving and distributing the stresses upon the screws by which the hinge 35 is held in place.

Other objects to be attained by the improvements embodied in my hinge will be apparent from the following description in which reference is made to the accompanying drawings, wherein—

Figure 1 is a view illustrating the hinge secured to a trunk. Fig. 2 is a view of the outer surface of the hinge. Fig. 3 is a view of the inner surface of the hinge. Fig. 4 is a longitudinal section substantially on the line 45 4—4 of Fig. 2, extending through both leaves of the hinge. Fig. 5 is a transverse section of one of the leaves of the hinge, substantially on the line 5—5 of Fig. 2. 50 Fig. 6 is a view of the inner surface of a modified form of hinge in which the inner

surfaces of the two leaves of the hinge are in different planes. Fig. 7 is a longitudinal section through both leaves of the hinge taken approximately along the line 7—7 of 55 Fig. 6. Fig. 8 is an end elevation of one of the leaves of the hinge illustrating the knuckles, and the struts which support the outer portion of the leaf; this view illustrating the end of that leaf which extends 60 inwardly beyond the plane of the coöperating leaf. Fig. 9 is an end elevation of the coöperating leaf which occupies a plane outwardly from the plane of the leaf illustrated in Fig. 8. 65

In the embodiment illustrated on sheet 1 of the drawings there is a leaf A and a coöperating leaf B. The leaf A is composed of metal having a flat portion 1 and a raised portion 2. The edges 3 of the raised portion 2 are in the same plane with the inner surface of the flat portion 1 and are adapted to bear against the surface to which the hinge is secured, as clearly illustrated in 70 Fig. 1. The outer surfaces of the edges are 75 curved, as shown in Fig. 5, thus presenting inclined surfaces at both sides of the hinge so that the hinge will slide readily without effecting a rigid abutment against the other hinges or objects with which the hinge may 80 come in contact. In this connection it may be mentioned that the hinge is especially adapted for use in connection with trunks, and the like, so that the novel features and 85 construction of the hinge and the novel functions may be more readily comprehended.

The pivoted end of the leaf A is formed with a series of knuckles 4, whose outer surfaces are flush with the outer surface of the 90 raised portion 2 of the hinge and whose inner surfaces are entirely above the inner surface of the flat portion 1 of the hinge and the edges 3, thus enabling the hinge to be secured in position without removing 95 any portions of the object to which the hinge is secured to receive the knuckles. Between the knuckles 4 and the side edges of the leaf the edge of the leaf is turned inwardly as indicated at 5, the said edge 5 being in the same plane with the inner surface of the flat portion 1 and the edges 3, thus 100

providing a rigid support adapted to bear against the surface to which the hinge is secured immediately adjacent to the knuckles. Portions 6 between the knuckles 4 are also turned inwardly to provide struts which are arranged to bear against the surface to which the hinge is secured and thus provide a very strong and rigid support to prevent compression of the raised portion of the leaf.

A number of holes 7 are formed through the flat portion 1 of the hinge for receiving the fastening devices by which the hinge is secured in place. The raised portion 2 of the hinge is formed with a number of countersunk portions 8 having holes 9. The holes 9 receive the fastening devices which extend through the raised portion of the leaf A, and the depressions within the countersunk portions 8 receive the heads of the fastening devices so that the heads will be flush with the outer surface of the raised portion of the hinge, thus preventing the fastening devices from becoming engaged with other objects.

In order to strengthen the hinge and to distribute the stress properly upon the fastening devices, I have provided an arch member 10 within the leaf A. In the form illustrated this arch member is secured between the countersunk portions 8 and is rigidly fastened in connection with the leaf A by a fastening device in the form of a rivet 11. The arch member abuts against the countersunk portions 8 and is thereby braced and strengthened in its position. The arch member 10 is provided with laterally extending portions 12 whose ends preferably engage against or terminate adjacent to the edge portions 3. It is preferable, though not essential, that the inner surfaces of the lateral extending portions 12 be in the same plane with the edges 3 and the inner surface of the flat portion 1 of the leaf, thus providing additional support for the raised portion of the hinge.

The lateral extensions 12 are provided with holes 13 which register with the holes 9 and through which the fastening devices extend, thus distributing the stress upon the fastening devices and preventing all of the stress from being thrown upon the fastening devices at a distance from the surface to which the hinge is secured.

The leaf B is similarly constructed, comprising a flat portion 14 and a raised portion 15 having inwardly turned edges 16 terminating in the same plane with the inner surface of the flat portion 14 and, in the embodiment illustrated on Sheet 1 of the drawings, in the same plane with the inner surface of the flat portion 1 and the edges 3 of the leaf A. Knuckles 17 are formed at the pivoted edge of the leaf B

and extend between the knuckles 4, the two leaves of the hinge being pivoted together by a hinge pin 18 passing through said knuckles. The edge of the raised portion laterally from the knuckles 17 is turned inwardly to form supporting edges 19 which bear against the surface to which the hinge is secured. A strut 20 is formed between the knuckles 17 and terminates in the same plane with the edges 16 and 19, thus constituting a rigid support for the intermediate portion of the raised part of the leaf.

Holes 21 are formed in the flat portion 14 of the leaf B for receiving the fastening devices, and countersunk portions 22 are formed in the raised portion of the leaf and provided with holes 23 for receiving the fastening device adjacent to the pivoted edge of the leaf. The countersunk portions 22 are of such depth that they will entirely receive the heads of the fastening devices, thus preventing them from becoming engaged with other objects.

An arch 24 is secured between the countersunk portions 22 by means of a rivet 25 and is formed with laterally extending portions 26 having holes 27 in axial alignment with the holes 23 for receiving the fastening devices which pass through the raised portion of the leaf. It is preferable that the laterally extending portions 26 shall be in the same plane with the edges 16 and the other supporting portions of the leaf, though in some instances a different arrangement may be preferred, and I do not restrict myself to this specific construction.

It will be understood that the hinge above described and as illustrated in Sheet 1 of the drawings is to be secured to surfaces extending in substantially the same plane. It is sometimes necessary or desirable to employ a hinge to be secured to surfaces in different planes. I have illustrated a hinge of the latter type on Sheet 2 in Figs. 6 to 9 inclusive of the drawings.

In the form of hinge illustrated in Figs. 6 to 9 there is a leaf C which, as shown, is precisely similar to the leaf B, comprising a flat portion 28 and a raised portion 29 having inwardly turned edges 30 and 31, and provided with knuckles 32. Countersunk portions 33 have holes 34 which receive fastening devices, there being an arch 35 secured in position by a rivet 36 and provided with lateral portions 37 having holes 38 registering with the holes 34 for receiving the fastening devices and distributing the stresses thereon.

The coöperating leaf D consisting of a portion 39 substantially in the same plane with the portion 28 of the leaf C, has a raised portion 40 which is in the same plane with the raised portion 29. An inwardly turned flange 41 extends inwardly beyond

the plane in which the portions 28 and 29 lie and is adapted to bear against the surface inwardly from the surface to which the leaf C is secured. The pivoted edge of the leaf D is formed with knuckles 42 between which the knuckles 32 extend and the two leaves of the hinge are pivoted together by a pin 43 passing through said knuckles. The portion 39 of the leaf D is provided with a number of holes 44 for receiving the fastening devices, and the raised portion 40 is provided with countersunk portions 45 having holes 46 through which the fastening devices extend, the heads of said fastening devices being entirely received within the countersunk portions 45. An arch member 47 is secured in position between the countersunk portions 45 by a rivet 48 and has laterally extending portions 49 extending to the side flanges 41. The lateral extensions 49 are provided with holes 50 which register with the holes 46 and receive the fastening devices and distribute the stress of the hinge thereon. Struts 51 are formed between the knuckles 42 and extend inwardly beyond the plane of the leaf C, and terminate in the same plane with the inner edge of the flanges 41, thus rigidly and firmly supporting the leaf D upon a plane inwardly from the plane of the leaf C.

What I claim and desire to secure by Letters Patent is:—

1. A hinge, comprising leaves having flat portions arranged to bear against the surface to which the hinge is secured and raised portions provided with holes for fastening devices, knuckles below the outer surface of said raised portions, a pin within said knuckles pivoting said leaves together, struts rigid with the inner sides of said raised portions and arranged to bear against the surface to which the hinge is secured, and members secured within said raised portions and having portions bearing against the surface to which the hinge is secured with holes in said bearing portions registering with the holes in said raised portions of the hinge to receive the fastening devices, substantially as described.

2. A hinge, comprising leaves having raised portions, knuckles formed on said raised portions, a pin passing through said knuckles and pivoting the leaves together, struts formed between said knuckles and arranged to bear against the surface to which the hinge is secured to support said raised portions, and a supporting member secured within the raised portion of each leaf for distributing the stress upon the fastening devices.

3. A hinge, comprising leaves having raised portions, knuckles formed on said raised portions, a pin mounted in said knuckles and pivoting said leaves together,

struts formed between said knuckles and 65 arranged to bear against the surface to which the hinge is secured, and a stress-distributing element secured in the raised portion of each leaf and bearing against said struts to distribute the stresses upon the fastening devices of the hinge. 70

4. A hinge, comprising leaves having raised portions, knuckles formed on said raised portions, a pivot pin in said knuckles, struts between said knuckles arranged to 75 bear against the surface to which the hinge is secured, flanges at the side edges of said leaves, members secured to said raised portion between said flanges and bearing against said struts, and means preventing 80 displacement of said members, substantially as described.

5. A hinge, comprising leaves having flat portions arranged to bear against the surface to which the hinge is secured and 85 raised portions, said flat portions and said raised portions having holes for the fastening devices, knuckles on said raised portions below the outer surface thereof, a pin within said knuckles pivoting said leaves together, 90 flanges forming rounded walls at the side edges of said raised portions, a member secured within the raised portion of each leaf having bearing portions to bear against the surface to which the hinge is secured and 95 having holes in said bearing portions registering with the holes in said raised portions for receiving the fastening devices, and struts formed on said raised portions between said members, and the pivoted 100 edges of said leaves and arranged to bear against the surface to which the hinge is secured, substantially as described.

6. A hinge, comprising a leaf including a raised portion, knuckles formed on said raised portion, an arch member having its two side portions arranged to bear against the surface to which the hinge is secured and having its outer portion bearing against the raised portion of the leaf, lateral extensions 105 on the side portions of said arch member having holes for receiving the fastening devices to distribute the stress thereon, and struts on said raised portion between said arch member and the pivoted edge of said leaf arranged to bear against the surface to which said leaf is secured. 110

7. A hinge, comprising leaves having raised portions provided with holes for the fastening devices, knuckles formed on said raised portions, a pin passing through said knuckles and pivoting the leaves together, an arch member secured within the raised portion of each leaf, laterally extending portions on said arches having holes registering with the holes in said raised portions for receiving the fastening devices to distribute the stress thereon, flanges at the side 120 125

- edges of said raised portions adjacent to the extremities of said laterally extending portions, and struts on said raised portions between said arch members and the pivoted edges of the leaves arranged to bear against the surface to which the hinge is secured, substantially as described.

In witness whereof, I have signed this specification in the presence of two subscribing witnesses.

LEWIS W. CHRISTOPHEL.
